Fig. 3.

UNITED STATES PATENT OFFICE.

CARL PETERS, OF SHERBURN, MINNESOTA.

DOOR LOCK.

Application filed July 26, 1923. Serial No. 653,908.

To all whom it may concern:

Be it known that I, CARL PETERS, a citizen of the United States, residing at Sherburn, in the county of Martin and State of Minnesota, have invented certain new and useful Improvements in Door Locks; and I do hereby declare the following to be a full, clear, and exact description of the invention, such as will enable others skilled in the art 10 to which it appertains to make and use the same.

This invention relates to a lock preferably of reciprocating bolt or latch type, and while the lock may have various applications, it is particularly designed to be used in a swinging door with the latch reciprocating in the edge of the door and handles disposed at each side of the door, the keeper for the lock being disposed in the door 20 frame.

It is an object of this invention to provide a door lock comprising three separate units which are readily insertable in and removable from the door and to which all parts of 25 the lock are attached so that there are no loose parts.

It is also an object of this invention to provide a lock of simple construction comprising a reciprocating latch and oscillating handles movable in planes substantially at right angles to the line of movement of said latch for operating the latch, together with means disposed at each side of the lock for preventing movement of said handles and latch, 30 thus locking the same in position.

It is a further object of the invention to provide a lock comprising spaced plates adapted to be attached at each side of the door, which plates carry bail-shaped or U-shaped grip handles movable in planes at 40 right angles to said plates, the ends of which project through said plates so as to be disposed therebetween and having an operating connection with a reciprocating member between said plates which, in turn, is connected to said latch, whereby movement of 45 said handles operates said latch.

It is a further object of the invention to provide such a lock as above set forth, the plate on the inside of the door carrying handle-operated means for locking the handles and latch against movement and the plate at the outer side of the door carrying key-operated means for locking said handles 50 and latch against movement.

It is more specifically an object of the invention to provide a lock comprising spaced plates adapted to be secured at each side of the door, which plates carry substantially U-shaped housings or guards in which are 60 mounted swinging U-shaped grip handles moving in planes at right angles to said plates, the inner ends of said handles projecting between said plates and having bars connecting their ends, which bars have projecting means at one side, respectively, engaging grooves formed in each side of a vertically reciprocating member disposed between said plates, said member having an aperture at its lower end from which is disposed one arm of a bell crank lever pivoted 70 between said plates, the other arm of which lever is disposed in an aperture in a stem projecting inwardly from a latch or bolt spring pressed outwardly. The plates of 75 said lock are preferably arranged so as to be spaced different distances apart.

These and other objects and advantages of the invention will be fully set forth in the following description made in connection so with the accompanying drawings in which like reference characters refer to the same parts throughout the different views, and in which,

Fig. 1 is a view in side elevation of the 85 lock showing the same applied to a door;

Fig. 2 is a view in elevation as seen from the right of Fig. 1;

Fig. 3 is a view in elevation of one portion of the lock carried by one plate thereof, the latch also being shown in section; and

Fig. 4 is a view in elevation of the other portion of the lock carried by the other plate thereof.

Referring to the drawings, a portion of 95 an ordinary swinging door, such as commonly used in dwellings, is shown as 1. The edge of the door has a plate 2 secured thereto by spaced screws, which plate may, in practice, be set into the door. Said plate 2 100 has a sleeve 3 projecting therefrom forming a guiding means for the bolt or latch 4 of the lock, which latch has an inwardly projecting stem 7 slotted to embrace a pin 5 extending through said sleeve and forming the abutment for one end of a coiled compression spring 6, the other end of which presses against the bolt 4. The bolt 4 is thus spring-pressed outwardly. The stem 7 is slotted at its inner portion and traversed 110

by a pin 8, a recess thus being formed between said pin and the body of said stem which is adapted to receive a depending hook forming one arm of a bell crank lever 9 to be later described, said bell crank lever, when operated being adapted to draw the latch or bolt 4 inwardly.

The lock comprises spaced plates 10 and 11 adapted to be disposed at each side of the door 1, the plate 11 having connected thereto by rivets or other suitable means, the heads of sleeves 12 which project toward plate 10, which latter plate is secured to said sleeves by screws threaded therein. Each plate 10 and 11 has secured thereto a housing or guard 13 of bail shape or substantially U-shape in form, the ends of which members 13 are secured to the plates 10 and 11 by small screws or rivets. The members 13 have loosely secured therein at their lower curved portions, small headed and nutted bolts 14 which pass through slots formed in the lower curved sides of bail-shaped or U-shaped grip handles 15 which are disposed in the members 13 and provided with flattened portions at their upper ends projecting through slots formed in the top portions of the members 13 so as to be guided therein; the lower portions of the handles 15 resting on washers 16 disposed on the bolts 14 and against the inner sides of the guards 13. The plates 10 and 11 are provided with slots through which project the upper and lower ends of the handles 15, said handles at their upper ends being provided with depending tongues 17 forming stop members limiting the inward movements of said upper ends when said handles are locked about the bolts 14. The inner ends of each handle 15 are connected by bars 18 rigidly secured thereto, one of said bars 18 being provided with a plate 19 having laterally extending slots 20 therein through which pass the bolts attaching it to the plate 18 so that the same can be adjusted to different positions with respect to plate 18 for a purpose to be later described. Each bar 18 has a pin 21 projecting inwardly therefrom, which pins are received in and move in slots 22 formed on each side of a vertically reciprocating plate member 23. The plate member 23 is thus disposed between the bars 18 and is provided adjacent its top and bottom ends with pins 24 projecting at each side and which travel in vertical slots formed in the sides of yoke-shaped clips 25 and 26, respectively. The yoke 26 is formed with a top embracing a screw 27 extending between the plate 11 and an upwardly extending projection attached to sleeve 12 and said yoke is provided with a slot 28 in which is disposed a revoluble nut 29 engaging the screw 27 so that the yoke clip 26 can be moved transversely between the plates 10 and 11. The yoke clip 25 is similarly

provided with a loop at its upper portion embracing a screw 30 projecting through plate 11 towards plate 10 and said yoke is provided with an adjusting nut 29^a similar to that shown and described for the yoke clip 26, which adjusting means is shown in Fig. 1. The lower end of member 23 is formed with an aperture 31 and one arm of the bell crank lever 9 is provided with a diagonal and downwardly extending slot 32 which embraces the portion of member 23 below the aperture 31, a portion of said arm thus passing through the aperture 31, as clearly shown in Figs. 1 and 3. The bell crank 9 is pivoted on the member 33 extending between the plate 11 and the projection upstanding from sleeve 12, which member has a head countersunk in plate 11 and has its other end threaded into the said projection and equipped with a lock nut.

The plate 11 is the plate which will be disposed on the outer side of the door and the same has attached thereto a lock casing 34 from the lower side of which operates a lock bolt 35. The casing 34 contains any suitable and simple form of mechanism for projecting and retracting the bolt 35 by means of a key inserted through the key sleeve 36, which means is not shown. The upper portion of handle 15 which extends through the plate 11 is provided with a slot 37 and the upper portion of the handle 15 which projects through plate 10 is also provided with a slot 38, one side of which is formed by the inner edge of the top portion of member 19. As shown in Fig. 1, when the handles 15 are disposed in their inner positions, the slots 37 and 38 are in alignment and if a key be inserted in the key slot in sleeve 36 and turned the bolt 35 will be projected into the slots 37 and 38 and the handles 15 will thus be locked against movement and it will be impossible to operate the latch bolt 4. It is possible to dispose the plates 10 and 11 at different distances apart to suit various thicknesses of doors and when this is done the plate 10 is moved relatively to plate 11. In order to then have the slot 38 register with slot 37 the member 19 can be adjusted laterally, owing to the slots 20, so that its upper inner edge will substantially align with the side of the bolt 35.

It is also desirable to have means for locking or setting the latch bolt 4 disposed on the inner side of the lock, and for this purpose a dog member 39 is pivoted flat against the plate 11 and this member has a pin or tongue 40 projecting between the plates 11 and 10 extending toward and almost to the latter plate. The dog 39 has a pin 39^a at its upper end which, when said dog is swung about its pivot, is adapted to enter an aperture 43 formed in the upper portion of each handle 15 which is disposed between plates

10 and 11. The plate 10 also has pivoted flat against the inner side thereof, a lever 41 which has a U-shaped sleeve 42 preferably formed integral therewith projecting 5 toward plate 11 in which the tongue 40 substantially fits and is adapted to slide. The lever 41 is provided with a tongue at its upper end which is received in a downwardly extending slot formed in a cam 10 lever 44 lying flat against the plate 10 and pivoted between the same and a plate 45 slightly spaced therefrom and secured thereto. The plate 44 is swung about its pivot by a cam 46 mounted on a stem 47 extending 15 through the plates 10 and 45 and the upper portion of housing 13, the outer end of which is provided with a flat operating handle 48. The lever 44 is held in either of two positions by a sear spring 49 disposed 20 about the top of the same between the plates 10 and 45 and extends under a pair of pins 50. The stem 47, as clearly shown in Figs. 1 to 4, is held in place by a split key. A pin 41^a in lever 41 is adapted to enter one aperture 25 43.

In operation, the latch bolt 4 will normally be projected by the spring 6. When either of the handles 15 are gripped by the hand and drawn toward the outer side of 30 the guards 13, it will be guided in the top of said guard and will swing about its point of contact with the washer 16. The respective bar 18 will thus be swung and the pin 21 thereon moved upwardly. This pin 35 will act on the upper side of the slot 22 and move the member 23 upwardly, said member being guided by the pins projecting therefrom and traveling in the slots in the yoke clips 25 and 26. The plate 23 will swing 40 upwardly, the inner arm of bell crank lever 9 and the lower arm of said bell crank lever will act on stem 7 and withdraw the latch bolt 4. The latch can thus be operated by either handle 15. When the handle is released, the member 23 will drop by gravity 45 and, through the action of spring 6, the latch will be again projected and the handles 15 moved to their inner position, being stopped by the stop lugs 17. If it is desired to set 50 the latch bolt 4 or prevent movement thereof from the inside of the door, the handle 48 will be turned and the lever 41 will then be swung about its pivot by lever 44, pin 41^a entering aperture 43. The sleeve 42 will 55 thus be swung about the pivot of lever 41 and will, in turn, similarly swing the tongue 40 which is attached to the dog 39. The said dog will then be swung about its pivot and the latch bolt 4 will be locked against movement. If it is desired to set the latch or 60 lock the same from the outside of the door, a key will be used and the latch bolt 35 will be projected into slots 37 and 38 and the handles 15 and latch bolt 4 thus prevented 65 from movement. The latch will then have

to be released by the use of the key. The lock is adapted to fit doors of varying thickness and for this purpose the plate 10 will be separated a greater distance from plate 11. When this is done the sleeve 42 will 70 merely slide on the tongue 40 and the pins 21 will merely slide in the slots 22. When the lock is thus widened it may be desirable to move the guide yokes 25 and 26 laterally and this can be done by moving the nuts 75 on the screws 27 and 30 and thus moving the said yokes laterally. As above described, it will also be necessary to adjust the plate 19 so that slot 38 can align with slot 37. When it is desired to remove the lock from the 80 door, the screws holding the plates 10 and 11 in place will merely be removed and the plate 10 drawn directly out. The plate 11 can then be swung outward at its upper end and taken out with a lifting movement so 85 that the tongue of the bell crank lever 9 will withdraw from its engagement with the stem 7. The latch and its assembled parts can then be withdrawn by removing plate 2. There are thus no loose parts in the lock 90 which may drop out and be difficult to replace. All of the parts are secured in position to one or the other of plates 10 and 11 and these plates, with their attached parts, form two units, as illustrated in Figs. 3 and 95 4. The lock can be placed in the door by merely reversing the movement described for removing the same.

From the above description it is seen that applicant has provided a simple and efficient lock mechanism and one that is easily operated and can be easily and quickly installed or removed. The parts of the device are all ruggedly made and secured in position and there is practically no chance 100 for the parts to become disarranged and thus cause the lock to get out of order. The device has been demonstrated in actual use and found to be very successful and efficient.

It will, of course, be understood, that various changes may be made in the form, details, arrangement and proportions of the parts without departing from the scope of applicant's invention, which, generally 115 stated, consists in a device capable of carrying out the objects above stated, such as shown and described and set forth in the appended claims.

What is claimed is:

1. A door lock comprising spaced plates adapted to be disposed at each side of the door, oscillating handles carried by said plates and movable in planes perpendicular to the sides of said door, a reciprocating means disposed and bodily movable vertically between said plates, means connecting said reciprocating means to said handles, a latch movable laterally between said plates, means connecting said latch to said 125 plates, means connecting said latch to said 130

- reciprocating means, means carried by one of said plates movable to engage both of said handles to prevent movement thereof and of said latch, and a handle at the outer 5 side of said plate for operating said means carried by said plate.
2. A door lock comprising spaced plates adapted to be disposed at each side of the door, oscillating handles carried by said 10 plates and movable in planes perpendicular to the sides of said door, a reciprocating means disposed and bodily movable vertically between said plates, means connecting said reciprocating means to said handles, a 15 latch movable laterally between said plates, means connecting said latch to said reciprocating means and key-operated means carried by one of said plates and adapted to prevent movement of said handles and latch.
- 20 3. A lock comprising a reciprocating latch, oppositely disposed handles mounted for swinging movement in planes at right angles to the movement of said latch, bars secured to said handles to move therewith, a member 25 bodily and vertically reciprocable in a plane at right angles to the movement of said latch, means on said bars engaging said member to reciprocate the same and articulated means connecting said member and said 30 latch.
4. A lock comprising parallel plates adapted to be disposed at each side of the door, a latch movable horizontally parallel to said plates, oscillating handles carried by said 35 plates and having portions extending therethrough, a vertically reciprocating member between said plates, a bar attached to each of said handles movable by the oscillations thereof, means on said bars engaging said 40 vertically reciprocating member, and means connecting said vertically reciprocating member and said latch whereby the latter is moved by movement of either handle.
- 45 5. The structure set forth in claim 4, and means carried by each plate for locking said handles and other parts against movement.
6. The structure set forth in claim 4, said handles having alining slots in their adjacent portions between said plates, and a 50 key-operated bolt carried by one of said plates adapted to enter said slots to prevent movement of said handles and said latch.
- 55 7. A lock comprising parallel plates adapted to be disposed at each side of the door, a latch movable horizontally parallel to said plates, oscillating handles carried by said plates and having portions extending 60 therethrough, a vertically reciprocating member between said plates, a bar attached to each of said handles movable by the oscillations thereof, means on said bars engaging said vertically reciprocating member,
- means connecting said vertically reciprocating member and said latch whereby the latter is moved by movement of either handle, said handles having alining slots in their adjacent portions between said plates, a key-operated bolt carried by one of said plates adapted to enter said slots to prevent movement of said handles and said latch, and a member forming one of said slots adjustable laterally with respect to 70 said plates.
- 75 8. The structure set forth in claim 4, one of said handles having an aperture therein disposed between said plates, a lever carried by the inner side of the one of said plates having means thereon adapted to enter said aperture, means carried by the other of said plates for swinging said lever, and handles on the outer side of said latter plate for operating said first mentioned lever to cause said means to enter said aperture.
- 80 9. A lock comprising parallel plates adapted to be disposed at each side of the door, a latch movable horizontally parallel to said plates, oscillating handles carried by said plates and having portions extending therethrough, a vertically reciprocating member between said plates, a bar attached to each of said handles movable by the oscillations thereof, means on said plates for 90 engaging said vertically reciprocating member, means connecting said vertically reciprocating member and said latch whereby the latter is moved by movement of either handle, one of said handles having an aperture therein disposed between said plates, a lever carried by the inner side of the one of said plates having means thereon adapted to enter said aperture, means carried by the other of said plates for swinging said lever, handles on the outer side of said latter plate for operating said first mentioned lever to cause said means to enter said aperture.
- 95 10. A lock comprising spaced plates adapted to be disposed at each side of a door, oscillating handles carried by said plates and having spaced portions extending through said plates so as to be disposed therebetween, a member reciprocable vertically between said plates having substantially horizontal grooves at each side thereof, bars connecting the said portions of each handle and carrying projecting pins movable respectively in said grooves to reciprocate said member, and a reciprocating latch bolt connected to said member.
- 110 11. The structure set forth in claim 10, said latch being spring-pressed outwardly and having an apertured stem at its inner

end, a bell crank lever pivoted between said plates having one arm engaging said apertured stem, said member having an aperture in its lower end in which the other arm of 5 said lever engages.

12. The structure set forth in claim 10, said member having means projecting therefrom adjacent each end thereof, and yoke 10 clips mounted between said plates and having slots therein in which said means are disposed for guiding said member, said yoke plates being adjustable toward and from said plates.

13. The structure set forth in claim 10, 15 and a stem and sleeve carried by said plates, respectively, and relatively slidably whereby said plates may be separated different distances, said projecting pins on the said portions of each handle sliding in said

grooves and said stem sliding in said sleeve 20 when said plates are moved apart.

14. A lock comprising spaced parallel plates adapted to be disposed at each side of a door, a housing member carried at the outer side of each plate, bail handles swingingly mounted in said housings and having spaced ends extending through said plates, a bar connecting said ends of each handle and disposed between said plates, a reciprocating member between said plates, means 25 at each side of said reciprocating member slidably engaged by means carried by said bars, and a latch reciprocating laterally parallel to said plates operatively connected to said reciprocating member. 30 35

In testimony whereof I affix my signature.

CARL PETERS.
